UNITED STATES PATENT OFFICE.

ELMER L. BARRETT, OF HAVELOCK, NEBRASKA, ASSIGNOR OF ONE-HALF TO LAWRENCE B. GUILD, OF HAVELOCK, NEBRASKA.

RAIL ANCHOR.

Application filed November 21, 1928. Serial No. 320,952.

This invention relates to improvements in rail anchors.

The primary object of this invention is the provision of an improved device for preventing the longitudinal creep of rails.

A further object of this invention is the provision of an improved rail anchor which is adapted to be effectively clamped upon a rail base and engaged upon a tie to prevent the longitudinal creep of the rail.

A further object of this invention is the provision of improved means for applying rail anchors to rails.

A further object of this invention is the provision of an improved method for constructing rail anchors.

Other objects and advantages of this invention will be apparent during the course of the following detailed description.

In the accompanying drawings, forming a part of this specification, and wherein similar reference characters designate corresponding parts throughout the several views,

Figure 1 is a plan view showing the improved rail anchor or anti-creep device with a tool for applying the same to a rail with respect to an adjacent road bed tie; the tie and rail being shown in dotted lines.

Figure 2 is a view showing the clamped relation of the rail anchor with respect to the rail and tie, which are shown in dotted lines.

Figures 3 and 4 are transverse sectional views taken substantially on their respective lines in Figures 1 and 2 of the drawings.

Figure 5 is a fragmentary side elevation of a rail and tie, showing a step by which the improved anchor is attached to the rail.

Figure 6 is a view showing the relation in which the anchor clamps upon a rail.

Figure 7 is a perspective view showing the improved rail anchor.

Figure 8 is a perspective view showing a tool for applying the rail anchor.

Figure 9 is a blank of flat stock steel or other metal, showing the manner in which it is initially constructed prior to bending of the details thereof to form the rail anchor.

In the drawings, wherein for the purpose of illustration is shown only a preferred embodiment of the invention, the letter A may generally designate the improved rail anchor, which is adapted to be applied upon the base of a rail B, and against a tie C, to hold the rail B against longitudinal creep-

ing action upon the tie C; an improved tool D being employed to effect the attachment of the anchor upon the rail and against the tie.

The improved rail anchor A is formed from a single piece of steel, suitably tempered, which is preferably bent to form from a blank sheet of flat stock material. The blank is preferably formed as shown in Figure 9, but cutting slots 20 and 21 parallel along the length thereof, from opposite ends thereof, said slots terminating short of the ends of the blank 19 opposite the ends upon which they respectively open. This divides the blank 19 into arm portions 22 and 23 along opposite sides thereof, and an intermediate cross or connecting portion 24. The blank 19 at the ends of the connecting portion 24 is bent upwardly on bending lines 25 and 26, to provide rail base edge engaging flanges 29 and 30, at opposite ends of the connecting portion 24, shown more particularly in Figure 7 of the drawings; the flange 29 being extended at right angles to the top surface of the connecting portion 24, and the flange 30 being relatively longer than the flange 29 and bent in an overhanging divergent relation with respect to the top surface of the connecting portion 24. The arm 23 is bent in a concavo-convex or segmental form in the plane of the intermediate portion 24, and transverse thereto, and at its free end the arm 23 is bent slightly radially outward as at 30^a and then upwardly to provide a lug or flange 31 which is adapted to be engaged against one side edge of the rail base in a relation to be subsequently described.

At the opposite side of the connecting portion 24 of the rail anchor, the arm 22, shown in Figure 9, is bent to provide a straight portion 34 divergent at an angle of less than 90° from the connecting portion 24, and lying in the same plane therewith; the arm 22 at the outer end of the portion 34 being turned to provide a downturned right angled portion 36, which is flattened and provides, in fact, a foot for engagement against a side of the tie C, to hold the anchor against relative movement along the road bed, as will be subsequently mentioned. It should be noted that the arm 23 is relatively long and is resilient, to provide a spring locking effect of the rail anchor upon the rail in a relation to be subsequently mentioned.

Referring to the application of the rail

anchor upon a rail, it is to be noted that the rail base engaging flanges 29 and 30, at opposite ends of the cross piece 24, have their rail base edge engaging surfaces spaced for a distance greater than the distance between the side edges of the rail base. This enables the rail anchor to be placed upon the rail, beneath the base thereof, with the cross piece 24 extending transverse to the length of the rail, and with the flange 30 hooked over one side margin of the rail base, as shown in Figure 3, and the other flange 29 engaging at the opposite side edge of the rail base. In this position the rail anchor may be slid longitudinally along the rail, beneath the same, until the depending foot 36 engages against a side of the tie C, in the position shown in Figure 5 of the drawings. The cross piece 24 is then swung diagonally across the rail base by pushing the flange end 29 towards the tie C, until the position shown in Figure 1 is reached, and it will be noted that the locking arm 23 is then entirely positioned beneath the rail base. A special tool D is then employed to flex the arm 23, against the normal spring action thereof, and bring the flanged end 31 thereof outwardly against the side edge of the rail base, to the position illustrated in Figure 2 of the drawings. This special tool D preferably consists of an elongated body 50, having one end 51 thereof flanged in right angled relation and bifurcated with a V-shaped recess 52. Spaced from the flange 51, and at the same side of the body 50 as flange 51 is a transverse extension 53 which has a finger 54 at the outer end thereof extending substantially parallel above the body 50 towards the end 51.

In operation, the lever D is fulcrumed at its end 51 upon a side edge of the rail base, with the recess 52 straddling the said margin of the rail base, as shown in Figures 1 and 5 of the drawings, and the finger 54 is hooked against the side of the rail anchor flange or lug 31, that is, with the flange or lug 31 received in the socket provided by the extension 53, at a point spaced from the fulcrum end 51. The lever 50 then having a fulcrum on the rail base is swung outward to flex the spring arm 23 and bring the flange end 31 thereof outwardly and upwardly against and outer edge of the rail base, to the position shown in Figure 2 of the drawings, and elsewhere. This places the spring arm 23 under tension, and locks the flanges 29 and 30 at opposite ends of the rail anchor cross piece 24, against the opposite sides of the rail base flanges, biting into the same, as shown in Figure 2 of the drawings. Inasmuch as the engaging foot 36 is disposed to one side of the longitudinal medial line of the rail, it is apparent that any tendency of the rail to creep over the tie C will cause the rail anchor at the flanges 29 and 30 to bite more effectively

into the rail base flanges, and preventing longitudinal creep of the rail over the tie C.

Various changes in the shape, size, and arrangement of parts may be made in the form of invention herein shown and described, without departing from the spirit of the invention or the scope of the claims.

I claim:

1. A rail anchor comprising a cross bar provided at opposite ends with portions adapted to engage the opposite sides of the rail base flange of a rail, a tie engaging foot extending transverse to the cross bar at one end of the cross bar, and a resilient rail clamping arm connected at the opposite end of the cross bar and adapted to engage the rail base flange at a side thereof to lock the cross bar at its rail base flange engaging ends against the rail base flange.

2. A rail anchor consisting of a single integral piece of metal comprising a cross bar provided with rail gripping portions at the ends thereof and having at one end thereof a tie engaging extension transverse thereto and at the opposite end thereof a resilient rail engaging arm transverse thereof at the opposite side of the bar from said tie engaging arm.

3. As an article of manufacture an anti-creep device for application to railway rails and adapted to be sprung into position upon the rail base, comprising a cross bar having rail base engaging extensions at opposite ends thereof, and a spring arm rigid with the cross piece and extending transversely thereto normally in an arc and having at an end thereof a rail base engaging extension.

4. As an article of manufacture a rail anchor comprising a cross bar adapted to be positioned beneath the base flange of a railway rail and at the ends thereof having extensions for engaging the sides of the rail base flange, means at one end of the cross bar which will engage a tie at one side of the longitudinal axis of the rail upon which the cross bar is positioned, and spring means adapted to engage the rail at the opposite side of its longitudinal axis to tip the cross bar so that the extensions at the ends thereof will engage in a locking relation with the sides of the rail base flange.

5. As an article of manufacture a rail anchor comprising a cross bar having rail base flange engaging extensions at the ends thereof, a transverse arm rigid with the cross bar adjacent one of said extensions and having a depending tie engaging foot thereon, and an arcuated spring locking arm rigid with the cross bar at the opposite end thereof with respect to the tie engaging foot, said locking arm having a rail base flange extension transverse thereon at the free end thereof.

6. The method of forming a rail anchor which consists in longitudinally slotting in

substantial parallelism a piece of blank metal inwardly from opposite ends thereof and terminating the slots at their opposite ends in the blank of material to provide side arms 5 and an intermediate cross portion, bending the metal at the ends of the cross portion and short of the dead ends of said slots trans-

verse to the cross portion to provide rail base flange engaging extensions, and bending the side arms formed by said slots transverse to 10 the cross portion to provide out of one of said arms a tie engaging arm and out of the other arm a spring locking arm.

ELMER L. BARRETT.
